UNITED STATES PATENT OFFICE.

JOHNSON S. WAUGH, OF SHEPARD, OHIO.

FREIGHT-CAR DOOR.

1,273,017.

Specification of Letters Patent. Patented July 16, 1918.

Application filed January 10, 1916. Serial No. 71,141.

To all whom it may concern:

Be it known that I, JOHNSON S. WAUGH, a citizen of the United States, residing at Shepard, in the county of Franklin and 5 State of Ohio, have invented a certain new and useful Improvement in Freight-Car Doors, of which the following is a specification.

This invention relates more particularly 10 to "flush" car doors, that is a sliding door which when closed has its outer or exposed side flush with the outer side of the car. A variety of constructions of such doors have been proposed but so far as I am aware 15 they have not gained very general approval and adoption because the supporting devices have been such as to require too much projection beyond the side of the car and have too much of their construction ex- 20 posed to the weather.

The object of my invention is to provide a construction which lessens the projection beyond the side of the car and simplifies and compacts the structure and at the same time 25 so far incloses it that the weather, particularly snowy, sleety weather, can have no serious effect in interfering with or preventing the operation of the door at any time.

The invention is embodied in the example 30 herein particularly shown and described and then pointed out in the claims.

In the accompanying drawings forming part hereof—

Figure 1 is a view in side elevation showing a portion of the side of a freight car 35 equipped with a door and hanger according to my invention.

Fig. 2 is a horizontal sectional view on the line $\alpha-\alpha$ Fig. 1 looking down.

Fig. 3 is a detail illustrating on a larger 40 scale a swiveled trolley employed in the construction.

Fig. 4 is a detail section on the line $y-y$ Fig. 1 but on a larger scale.

Figs. 5 and 6 are detail views in horizontal 45 section and plan view showing cams or guiding members on the car and door for forcing the door into closing or flush position when the door is slid into place opposite the door opening.

In the views 6 designates the side of a car and 7 the door the latter having a handle 7^a by which it may be moved. To the upper edge of the side of the car in the corner 55 under the eave of the roof is secured a strip

of wood 8, and upon the outer face of this strip is secured a metallic hood. The strip of metal constituting this hood is made generally of two widths as seen at 9 and 10 and each portion has its lower edge bent inward 60 toward the car to form tracks 9^a and 10^a. The track 10^a has a continuation 10^b in a very narrow portion that is curved toward the car and secured thereto. The hood and track 9^a are likewise curved toward the car. 65 These curved portions are so formed that a door supported and slideable upon the tracks as hereinafter described is directed toward the door opening or away therefrom according to the direction of force applied to the 70 door.

The door is provided with suitable rollers 11 and 12 journaled in one leg of J-shaped frame carried by a plate adapted to be secured to the upper portion of the door. 75 The J-shaped frame is adapted to embrace the lower edge of the hood including the track so as to keep the door on the track and aid in guiding it into and out of closing position. Either or both of the J-shaped 80 frames can be swiveled to the securing plate as shown in Fig. 3. The lower edge of the door is guided and kept in position by suitable guiding members 14 and 15 secured to the side of the car near the lower corners of 85 the doorway. The guiding member 15 is shown to have its operative portion more offset than that of member 14 for the purpose of providing room for the outward movement of that portion of the door when 90 the door is opened. A long finger 16 on the lower right hand corner of the door is provided to coöperate with this more offset guiding member in forcing the lower portion of the door to closing position when 95 closing movement is given to it.

A suitable latch can be provided for securing the door in closed position. The latch shown consists of a sliding and rocking bolt 17 mounted in a plate 18 in the 100 door, said bolt having a pendant loop 17^a to embrace a staple 19 when the bolt has been thrown to engage a bolt catch 20 on the jamb or side of the car next the door opening. When the bolt has been manipulated to place it in latching position it can be there held by a pin 21 slid through the staple beyond the loop 17^a of the bolt. To hold the bolt in unlatched position the bolt receiving plate or frame 18 is provided with 105 110

an intermediate projection 22, between which and said frame, the loop 17^a falls and is held by gravity.

23 designates a stop on the side of the car to limit the opening movement of the door; and 24 designates a bracket to support the opened door in case it sags or to prevent its sagging on its hangers.

In practice, to open the door, the handle 7^a is grasped and pulled outward from the car and to the right until open as far as desired, or until open as far as may be, as shown by broken lines Fig. 2. To close the door it is slid to the left, pressure being applied to carry it inward until flush with the side of the car. The hood imparts rigidity to the structure and prevents access of snow and ice to the tracks and trolleys to interfere with the operation of the door in the winter season.

The forms of the parts can be changed without departing from the gist of the invention as claimed.

What I claim is:

25 1. In combination with a freight car hav-

ing a door opening, a door, a supporting device for the door consisting of a hood secured near the eave of the car, said hood having two lower edges one above the other bent inward toward the car and constituting tracks independent of each other, said tracks having portions curved abruptly and substantially parallel toward the door and a roller for each track on the door to travel on said tracks.

2. In combination with a freight car having a door opening, a door, a supporting device for the door consisting of a hood secured near the eave of the car, said hood having lower edges one above the other bent inward toward the car and constituting tracks, said tracks also having portions abruptly and substantially parallelly curved toward the car, and a roller for each track on the door to travel on said tracks, said rollers each having a mounting adapted to embrace the under side of the track and the outer side of the hood.

JOHNSON S. WAUGH.
